UNITED STATES PATENT OFFICE

2,050,502

IRONING MACHINE

Claude A. Pickens, Spokane, Wash.

Application April 10, 1935, Serial No. 15,702

13 Claims.

(Cl. 38—28)

This invention relates to an improved ironing machine and one object of the invention is to provide a machine including a standard carrying a board and having an iron associated with the board and controlled by hydraulic means which will not only regulate pressure applied by the iron but also control movements thereof during an ironing operation and thus permit any desired pressure to be applied and the iron very easily moved.

Another object of the invention is to provide a device of this character wherein the iron holding and operating means is practically entirely enclosed in a standard or housing where it will be shielded and protected from damage.

Another object of the invention is to provide a housing which not only serves very effectively as a housing for enclosing the operating mechanism but also will constitute a substantial support for an ironing board and have sufficient weight to prevent any danger of the apparatus turning over when in use.

Another object of the invention is to provide an apparatus of this character wherein the hydraulic means for controlling movement of an iron toward and away from a board and along a board may be independently controlled through the medium of valves actuated from a single pedal and thereby permit the device to be very easily operated by foot action and leave the hands free for moving a garment to be pressed into its proper position upon the board and also allow the hands to be employed for guiding the iron.

The invention is illustrated in the accompanying drawings, wherein

Figure 1 is a view showing the improved ironing machine in side elevation.

Figure 2 is a top plan view thereof.

Figure 3 is a sectional view taken vertically through the ironing machine.

Figure 4 is a fragmentary sectional view taken along the line 4—4 of Figure 3.

Figure 5 is a diagrammatic view of the hydraulic means for controlling movements of the iron.

Figure 6 is a fragmentary sectional view taken along the line 6—6 of Figure 3.

Figure 7 is a fragmentary view of the mechanism for controlling movement of the iron toward and away from the ironing board.

Figure 8 is an enlarged view of the treadle and mounting thereof.

This improved ironing machine includes a

standard or pedestal 1 which may be referred to as a vertically disposed casing. The pedestal has an enlarged base 2 which is of sufficient dimensions to cause the pedestal to be firmly supported in an upright position and at its upper end the pedestal is formed with a head 3 which is smaller in dimensions than the base but is elongated substantially parallel to the base, as shown in Figure 2. A bracket 4 is secured to the pedestal at the front thereof and extends forwardly and then upwardly, as shown clearly in Figures 1 and 3 and by referring to Figures 3 and 4 it will be seen that at its upper end the bracket is formed with a socket 5 to receive the stub shaft or shank 6 of the ironing board 7. A side opening 8 is formed at the front of the socket 5 to receive a pin 9 carried by the shank 6 and, therefore, while the ironing board may be turned with the shank 6 as a pivot, its turning movement will be limited by the pin 9 contacting with the socket at sides of the opening 8.

Within the head 3 of the standard there is disposed a tube 10 of strong metal which may be referred to as a track and upon referring to Figure 3 it will be seen that this tube extends longitudinally in the head and at its ends is supported in mountings 11 and 12. A rod or shaft 13 extends longitudinally in the tube and carries discs 14 which are eccentric to the rod or shaft and are rotatable with the shaft. It will thus be seen that when rotary motion is imparted to the shaft and discs, the shaft will be shifted vertically of the standard in the tube and the extent to which a hanger 15 extends downwardly through a slot 16 formed longitudinally of the tube will be regulated. The hanger is slidable along the shaft 13 and to this hanger is attached an arm 17 which may be referred to as an iron carrier and projects outwardly from the standard through a slot 18 formed vertically of the standard at the front thereof above the bracket 4. At its forward end, the arm extends downwardly and is hinged or pivotally mounted to a bracket 19 which is connected with the iron 20 by a pin 21 constituting a pivot about which the iron may be turned as a vertical axis and it will thus be seen that the iron may have rocking movement longitudinally of the arm 17 and also turned about the pin 21 as an axis and guided in its movements upon the ironing board. Therefore, when a garment or other article to be pressed is applied to the board and the iron moved downwardly into operative engagement with the garment, the handle 22 of the iron may be grasped and the iron guided similar to the manner in which a

flat iron is used. This iron is to be electrically heated and is provided with a terminal 23 to which the terminal 24 of a conductor 25 is detachably connected. The conductor 25 extends along the 5 arm 17 to the back of the standard and may be connected with any suitable source of current supply. By this arrangement the terminal 24 may be readily detached and prevent overheating of the iron.

10 The arm 17 is to be shifted longitudinally for reciprocating motion upon the ironing board and, therefore, its rear or inner end is pivotally mounted through the medium of a shaft 26 which projects from opposite sides of the arm and is 15 engaged in bearings formed at lower ends of plates 27 which are connected by cross pins 28 and form a carriage, indicated in general by the numeral 29. This carriage is disposed about the tube 10 and upon the cross pins 28 are mounted 20 rollers 30 which bear against upper and lower portions of the tube and not only permit the carriage to slide easily along the tube as a track, but also serve to retain the carriage in its proper position relative to the track. A rocker bar or 25 lever 31, which extends upwardly in the standard, is pivotally mounted upon a shaft 32 journaled transversely in the standard and at its upper end this lever is formed with forks 33 which straddle the arm 17 and the carriage and are formed with 30 longitudinally extending slots 34 in which end portions of the shaft 26 are engaged. Rollers may be provided about ends of the shaft 26 in order to permit the shaft and rocker arm or lever to move easily relative to each other. It 35 will be readily understood that when rocking motion is imparted to the lever, the carriage will be shifted longitudinally upon the track or tube 10 and the arm 17 and iron reciprocated longitudinally of the ironing board. It will, therefore, 40 only be necessary for the operator to direct the movement of the iron by grasping the handle 22 and turning the iron about its pivot 21 and thus cause the iron to move in the proper direction across a garment to be pressed.

45 Vertical adjustment of the iron and reciprocating movement thereof is controlled by the mechanism shown in Figure 3 and also in Figures 5 through 8. Referring to these figures it will be seen that a pair of cylinders 35 and 36 are mounted vertically in the standard or casing 1 with the rods 37 and 38 of their pistons 39 and 40 extending upwardly from the cylinders. The piston rod 37 is loosely connected with the lower end of a rod or elongated link 41 which extends 50 upwardly through the standard and has its upper end attached to a crank arm 42 carried by and extending radially from the rear end of the shaft 13. When the piston is moved upwardly to rotate the shaft 13, its eccentric relation to the 55 discs 14 will cause the shaft 13 to be shifted downwardly in the tube 10 and, therefore, the arm 17 and the iron will be lowered to bring the iron into contact with the ironing board. The extent of movement imparted to the piston will regulate 60 downward movement of the arm 17 and iron and, therefore, the pressure exerted by the iron may be controlled. Downward movement of the piston rod and link 41 will rotate the shaft 13 in the opposite direction and the arm 17 and iron 65 will be elevated and the iron moved out of engagement with the ironing board. The piston rod 38 has its upper end pivotally mounted between the forks 43 at the lower end of the rocker arm or lever 31 by a pin 44 which is received in 70 slots 45 formed longitudinally in the arms or 75

forks 43 and it will be readily seen that when the piston 40 is moved downwardly to exert pull upon the forks 43, the rocker arm 31 will be swung forwardly and move the iron toward the forward end of the ironing board, whereas when the piston is shifted upwardly in its cylinder, the rocker arm or lever will be swung rearwardly and the iron moved toward the rear end of the ironing board. Therefore, a reciprocating motion may be imparted to the iron without the operator personally exerting physical force upon the iron. 10

The pistons 39 and 40 are to be moved by hydraulic force. In order to do so, there has been provided a pump 46 mounted in a sump or oil container 47 and connected with an electric motor 48 mounted upon the bottom of the standard or pedestal, as shown in Figure 3. A pipe 49 extends upwardly from the pump through the top of the oil container and at its upper end is provided with a cross head 50 which communicates with the casings of the two valves 51 and 52. Pipes 53 and 54 lead from the casing of the valve 51 to upper and lower ends of the cylinder 35 and corresponding pipes 55 and 56 lead from the casing of the valve 52 to upper and lower ends of the cylinder 36. There have also been provided pipes 57 and 58 which lead from the two valves and communicate with a pipe 59 which may be referred to as a return pipe and leads to the sump or oil container 47. Valve blocks 60 and 61 are 20 rotatably mounted in the casings of the valves and formed with arcuate passages 62, 63, 64, and 65. From an inspection of Figure 5 it will be seen that with the valve blocks set in the position shown, oil forced upwardly through the pipe 49 will flow through the passages 60 and 64 and pipes 53 and 55 into the upper ends of the cylinders 35 and 36 to force the pistons downwardly. During this movement, oil in the cylinders below the pistons will be forced through the pipes 54 and 56 and passages 63 and 65 into the pipes 57 and 58 to the pipe 59 and into the oil container. By turning the valve blocks to move their passages to the positions indicated by dotted lines in Figure 5, the direction in which the oil flows will be reversed and the oil will enter the lower ends of the cylinders to move the pistons upwardly and oil in the cylinders above the pistons will be returned to the oil container. By turning the valve blocks to positions in which their passages will be out of registry with the pipes, flow of oil will be cut off. It will thus be seen that flow of oil may be individually regulated and, therefore, the iron may be moved downwardly to a position in which it will engage the ironing board or an article placed thereon until the desired pressure will be exerted and the valve 51 then shut off after which the valve 52 may be adjusted to control directional movement of the piston 40 and reciprocating movement imparted to the iron. 40 This movement may be the full stroke of the piston or short strokes. 50

The two valves are to be actuated by one foot of the operator and in order to do so there has been provided a treadle 66 which is pivoted to a 65 plunger 67 slidably mounted in a cup 68 which extends vertically in the forward portion of the base 2 of the pedestal. A spring 69 resiliently supports the plunger 67 and, therefore, the treadle 66 and plunger will remain in the elevated position shown in Figures 3 and 8 until sufficient pressure is exerted upon the treadle to overcome the action of the spring. A rocker bar 70 which extends longitudinally in the base 2 is pivotally mounted, as shown at 71, and extends through a 70 75

slot 72 formed in the base with its outer end pivoted to the plunger 67 by the pin 72 which pivotally connects the treadle with the upper end of the plunger. The inner end of the rocker bar is 5 pivoted to a link 73 extending upwardly in the pedestal and connected to the crank arm 74 of the valve 71 and by referring to Figure 3 it will be readily seen that by pressing upon the treadle to depress the plunger 67, the block of the valve 10 51 may be moved to an adjusted position and when pressure is released to allow the plunger to return to its elevated position, the block of this valve will be returned to the original position. The crank arm 15 of the valve 52 is engaged by 15 a link 16 extending vertically in the pedestal and having its lower end pivoted to a link 17 which extends outwardly through the slot 12 and at its outer end is rigidly engaged with the treadle 66. By rocking the treadle toward the pedestal to move the link 17 inwardly and swing its inner 20 end downwardly, pull will be exerted upon the link 16 to adjust the valve 52 and by rocking the treadle in an opposite direction to swing the inner end of the link or rod 17 upwardly, the position of the valve block 61 may be reversed. It 25 will thus be seen that by imparting rocking movement to the treadle, the rocker arm 31 will be oscillated and reciprocating motion imparted to the carriage 29, arm 17 and iron. The speed at 30 which the valve is adjusted will regulate reciprocation of the arm 17 and the iron and control extent to which the iron travels. Therefore, short rapid strokes may be imparted to the iron or longer strokes at a slower rate of speed. Provision 35 has also been provided for automatic adjustment of the valve 52 in case long strokes are desired. This consists of providing a rod 78 which is pivoted at its lower end to the crank arm 75 and extends upwardly with its upper end pivoted to an arm 79 which is loosely mounted upon the pin or shaft 32 and carries depending lugs 80 and 81. The bearing 82 at the lower end of the rocker arm 31 carries a finger 83 which extends between the fingers 80 and 81 and it will be readily seen 40 from an inspection of Figure 3 that as the rocker arm 31 is oscillated its full extent, the finger 83 will be alternately moved into engagement with the fingers 80 and 81 imparting rocking movement to the arm 79 to raise or lower the link 78 and 45 adjust the valve 52 to reverse movement of the piston 40. Engagement of the finger 83 with one of the fingers 80 or 81 takes place just prior to the rocker arm reaching the limit of its movement in either direction and, therefore, the valve 52 will be adjusted in proper timed relation to 50 movement of the rocker arm. It will thus be seen that reciprocation of the iron may be automatically controlled or manually controlled and that if long strokes of the iron are desired, the valve 51 55 may be moved to lower the iron to apply desired pressure and the valve 57 then permitted to be automatically adjusted. If short strokes are desired the valve 52 will be manually adjusted by properly rocking the treadle. When it is desired to raise the iron in order to remove a garment or shift it into position to bring an unpressed portion under the iron, the block of the valve 52 will be moved to shut off movement of the piston 40 and the valve 52 then adjusted to raise the iron. 60 By having the ironing board pivotally mounted in the socket 5, the board may be turned from the position in which it extends longitudinally of the base and iron to a position diagonally thereof. It should also be noted that the ironing board 65 has been provided with side extensions 84 which

are detachably held in place by metal strips 85 fixed to their under faces and engaged in clips 86 attached to the under face of the ironing board.

Having thus described the invention, what is claimed as new is:

1. In an ironing machine, an ironing board, an iron over said board, an elevated track, an arm slidably and tiltably connected with said track and having an end portion disposed over the board and connected with the iron to support the iron, hydraulic means for imparting sliding movement to the arm and thereby reciprocating the iron, hydraulic means for pivoting the arm vertically and thereby moving the iron into and out of engagement with the board, and actuating means common to both hydraulic means.

2. In an ironing machine, an ironing board, an overhead track, a carriage slidable along said track, an arm pivoted to said carriage for vertical movement, an iron carried by said arm over the board, means for tilting the arm about the pivot and supporting the arm in a vertically set position and thereby vertically adjusting the iron relative to the board, hydraulic means for reciprocating the carriage along the track including a control valve, hydraulic means for adjusting the supporting means including a control valve, and operating means for said valves.

3. In an ironing machine, an ironing board, an overhead track, a carriage slidable upon said track, an arm pivoted to said carriage, an iron carried by said arm and disposed over said board, a hanger for supporting the arm and iron in a vertically adjusted position relative to the board, hydraulic means for effecting movement of the carriage and vertical adjustment of the arm including a cylinder and piston for effecting sliding of the carriage and a cylinder and piston for effecting adjustment of the arm, a pump common to both cylinders, a valve associated with each cylinder, and means for independently adjusting the valves.

4. In an ironing machine, an ironing board, a track, a carriage slidable along said track, a hanger shiftable longitudinally of the track, an arm pivoted at one end to said carriage and intermediate its length being pivoted to said hanger, said arm having its other end disposed over the ironing board, an iron carried by the said end of said arm and being movable relative to the arm, means for vertically adjusting the position of said hanger to tilt the arm vertically and move the iron toward and away from the ironing board having fluid actuated operating means including a control valve, means for shifting said carriage along the track having fluid actuated operating means including a control valve, and means for individually adjusting said valves.

5. In an ironing machine, an ironing board, an iron carrier adjustable vertically toward and away from the ironing board and mounted for reciprocating movement horizontally over the board, hydraulic means for effecting vertical adjustment of the carrier including a cylinder and a piston slidably longitudinally therein, hydraulic means for effecting reciprocation of the carrier including a cylinder and a piston slidably longitudinally therein, a fluid pump, conduits for delivering fluid from said pump to the cylinders and returning the fluid to the pump, valves for independently controlling flow of fluid from the pump through the cylinders and regulating directional flow of the fluid through the individual cylinders for controlling directional movements of the pistons and thereby of the carrier, actuating rods operatively

connected with said valves, and an operating element common to the rods of both valves.

6. In an ironing machine, a standard, an ironing board mounted in front of said standard, a track extending horizontally in the standard above the ironing board, a carriage slideable along said track, an arm pivoted to said carriage and projecting from the standard over the ironing board, an iron carried by said arm, a hanger for said arm shiftable longitudinally of the track with the arm and carriage, means for shifting the carriage along said track having fluid actuated actuating means, means for adjusting the hanger vertically having fluid actuated actuating means, and means for individually controlling the hydraulic actuating means.

7. In an ironing machine, a standard, an ironing board in front of said standard, a tubular track extending horizontally in the standard above the ironing board, a shaft extending longitudinally in said track and rotatably mounted by discs eccentric to the shaft, a hanger carried by said shaft and shiftable along the same, a carriage slideable along said track, an iron carrying arm pivoted to said carriage and pivoted to said hanger, said arm projecting from the standard over the ironing board, a rocker arm extending vertically in said standard and pivotally mounted at its lower end, the upper end of the rocker arm being pivotally and slidably connected with the carriage for reciprocating the arm when the rocker arm is moved, a rod extending vertically in said standard and having its upper end connected with said shaft for imparting rotation to the shaft and discs to vertically adjust the shaft and hanger and move the outer end of the arm toward and away from the ironing board, fluid actuated means for operating the rocker arm, fluid actuated means for shifting said rod vertically in the standard, a pump for supplying fluid under pressure to both of the fluid actuated means, valves for controlling flow of fluid to the fluid actuated means and governing directional flow of the fluid, and means for individually adjusting the valves.

8. In an ironing machine, a standard, an ironing board in front of said standard, a tubular track extending horizontally in the standard above the ironing board, a shaft extending longitudinally in said track and rotatably mounted by discs eccentric to the shaft, a hanger carried by said shaft and shiftable along the same, a carriage slideable along said track, an iron carrying arm pivoted to said carriage and pivoted to said hanger, said arm projecting from the standard over the ironing board, a rocker arm extending vertically in said standard and pivotally mounted at its lower end, the upper end of the rocker arm being pivotally and slidably connected with the carriage for reciprocating the arm when the rocker arm is moved, a rod extending vertically in said standard and having its upper end connected with said shaft for imparting rotation to the shaft and discs to vertically adjust the shaft and hanger and move the outer end of the arm toward and away from the ironing board, fluid actuated means for controlling movements of the rod and rocker arm, and means for controlling operation of the fluid actuated means and individually imparting movements to the rod and rocker arm and regulating extent of the movement.

9. In an ironing machine, a standard, an ironing board in front of said standard, a tubular track extending horizontally in the standard

above the ironing board, a shaft extending longitudinally in said track and rotatably mounted by discs eccentric to the shaft, a hanger carried by said shaft and shiftable along the same, a carriage slideable along said track, an iron carrying arm pivoted to said carriage and pivoted to said hanger, said arm projecting from the standard over the ironing board, means for imparting reciprocating movement to the carriage and iron carrying arm having fluid actuated actuating means adapted to regulate the extent of movement imparted to the arm, and means for rotating the shaft and discs to vertically adjust the hanger and arm and shift an iron carried by the arm toward and away from the ironing board having fluid actuated actuating means.

10. In an ironing machine, a standard, an ironing board in front of said standard, a track extending horizontally in said standard, a shaft extending longitudinally of said track, a carriage slideable along said track, an iron carrying arm pivoted to said carriage and suspended from said shaft and shiftable longitudinally of the track with said carriage, a rocker bar extending vertically in said standard with its upper end engaging the carriage and its lower end pivotally mounted, a rod shiftable vertically in said standard for adjusting the position of said shaft and moving an iron carried by the arm toward and away from the ironing board, cylinders in said standard, pistons in said cylinders connected with the rod and the rocker bar for actuating the same when the pistons are moved, valves associated with said cylinders, a pump having a pipe leading therefrom to said valves, and means for individually adjusting said valves.

11. In an ironing machine, a standard, an ironing board in front of said standard, a track extending horizontally in said standard, a shaft extending longitudinally of said track, a carriage slideable along said track, an iron carrying arm pivoted to said carriage and suspended from said shaft and shiftable longitudinally of the track with said carriage, a rocker bar extending vertically in said standard with its upper end engaging the carriage and its lower end pivotally mounted, a rod shiftable vertically in said standard for adjusting the position of said shaft and moving an iron carried by the arm toward and away from the ironing board, cylinders in said standard, pistons in said cylinders connected with the rod and the rocker bar for actuating the same when the pistons are moved, valves associated with said cylinders, a pump having a pipe leading therefrom to said valves, manually controlled means for adjusting said valves, and means actuated by the rocker bar for adjusting the valve of the cylinder having the piston connected with the rocker bar.

12. In an ironing machine, a standard, an ironing board in front of said standard, a track extending horizontally in said standard, a shaft extending longitudinally of said track, a carriage slideable along said track, an iron carrying arm pivoted to said carriage and suspended from said shaft and shiftable longitudinally of the track with said carriage, a rocker bar extending vertically in said standard with its upper end engaging the carriage and its lower end pivotally mounted, a rod shiftable vertically in said standard for adjusting the position of said shaft and moving an iron carried by the arm toward and away from the ironing board, cylinders in said standard, pistons in said cylinders connected with the rod and the rocker bar for actuating the same when the pistons are moved, valves asso-

ciated with said cylinders, a pump having a pipe leading therefrom to said valves, handles for said valves, rods pivoted to the handles and depending therefrom, a lever extending horizontally in the lower portion of said standard and pivotally mounted intermediate its length, the inner end of said lever being pivoted to the lower end of one rod, a plunger slideable vertically and yieldably held in a raised position, the outer end of 10 said rod being pivoted to the upper end of said plunger, a pedal pivoted to the upper end of said plunger, and a link extending horizontally in the lower portion of the standard with its outer end rigidly fixed to the pedal and its inner end 15 pivoted to the lower end of the other rod.

13. In an ironing machine, a standard, an ironing board in front of said standard, a track extending horizontally in said standard, a shaft extending longitudinally of said track, a carriage 20 slideable along said track, an iron carrying arm pivoted to said carriage and suspended from said shaft and shiftable longitudinally of the track with said carriage, a rocker bar extending ver-

tically in said standard with its upper end engaging the carriage and its lower end pivotally mounted, a rod shiftable vertically in said standard for adjusting the position of said shaft and moving an iron carried by the arm toward and away from the ironing board, cylinders in said standard, pistons in said cylinders connected with the rod and the rocker bar for actuating the same when the pistons are moved, valves associated with said cylinders, a pump having a pipe leading 10 therefrom to said valves, handles for said valves, rods pivoted to the handles and depending therefrom, manually operated means connected with said rods for individually adjusting the valves, a lever pivotally mounted at the lower end of said 15 rocker bar, a link connecting said lever with the handle of the valve associated with the cylinder having its piston connected with the rocker bar, lugs carried by said lever, and a finger carried by the rocker bar for engaging the lugs and effect- 20 ing automatic adjustment of the valve when the rocker bar is in motion.

CLAUDE A. PICKENS.
